DESIGN FOR A WASHING MACHINE

Dave Hirstel, San Francisco, Calif., assignor of one-half to Ferdinand Bendheim, San Francisco, Calif.

Application June 10, 1936, Serial No. 63,196

Term of patent 14 years

To all whom it may concern:

Be it known that I, Dave Hirstel, a citizen of the United States, residing in the city and county of San Francisco, State of California, have invented a new, original, and ornamental Design for a Washing Machine, of which the following is a specification, reference being had to the accompanying drawing, forming a part thereof.

chine, showing my new design.

I claim:
The ornamental design for a washing machine
as shown.

DAVE HIRSTEL.
